UNITED STATES PATENT OFFICE.

ERNEST J. VERRUE, OF SAN FRANCISCO, CALIFORNIA.

AMALGAMATOR.

SPECIFICATION forming part of Letters Patent No. 625,909, dated May 30, 1899.

Application filed August 23, 1897. Serial No. 649,165. (No model.)

To all whom it may concern:

Be it known that I, ERNEST J. VERRUE, a citizen of the United States, residing at San Francisco, in the county of San Francisco and State of California, have invented certain new and useful Improvements in Amalgamators; and I do hereby declare that the following is a full, clear, and exact description thereof.

This invention relates to a certain new and useful gold-amalgamator designed for use more especially for recovery of what is known as "float-gold" or the precious metal from that class of ore commonly known as "black sand;" and it consists in the arrangement of parts and details of construction, as will be hereinafter fully set forth in the drawings and described and pointed out in the specification.

Owing to the fineness of the float-gold or that contained in black sand it has been found impossible to successfully treat the same in the ordinary belt or table concentrator, for the reason that the water necessary to run over the concentrator to separate the gold from the sand or base material and convey the sand or material from the concentrator carries therewith so much of the fine gold as to render such style of machine inexpedient for the treatment of this class of material.

The object of my invention is to provide a simple and inexpensive apparatus for successfully treating float-gold or recovering the precious metal from black sand, although it is equally as well adapted for the working of any well-pulverized ore.

In order to fully understand the invention, reference must be had to the accompanying sheet of drawings, forming a part of this application, wherein—

Figure 1 is a vertical sectional view in elevation of the amalgamator, taken on line $x-x$, Fig. 2; and Fig. 2 is a top plan view of the amalgamator.

In the drawings the letter A is used to indicate any suitable base-frame, to which is secured a series of standards A', upon which standards rests the circular flange or rim a of the amalgamating-pan B. This pan is preferably dish-shaped and is formed with the central upwardly-projecting cone-shaped hub B', which hub is cast with the worm-thread

a'. The cone-shaped hub B' terminates in a stem a², which fits within a socket b, formed in the lower end of the vertical shaft B². This shaft is connected at its lower end by cross-ribs b' to the inner wall of the inclined drive-hopper B³, which hopper forms a part of conical-shaped inner wall C of the inner shell C'. This shell fits within the dish-shaped pan B, and its wall is outwardly flared to correspond with that of the amalgamating-pan. The distance between the outer wall of the inner shell C' and the inner wall of the pan B is so regulated as to leave an annular passage-way b² therebetween, through which the material to be worked is forced. The upper end of the vertical shaft B² extends through a bearing-hub d of the angle-arms C², which arms at their lower ends are bolted to the circular flange or rim a, Fig. 1.

By reference to Fig. 1 of the drawings it will be noticed that the outer face of the hopper B³ is provided with the grooved circular ribs 1 2 3. These grooved ribs enable me to dispense with belt-wheels and connections for driving or rotating the said hopper, for the drive-belt 4 is placed around either of the said grooved ribs, in accordance with the speed desired to be attained.

In the wall of the amalgamating-pan is formed the circular groove d' and the pockets d², the former being at approximately the base of the cone-shaped hub B' and the latter at a point near the top of the said pan. The passage-way b² is filled with quicksilver to about the point 6, and any quicksilver which is splashed or forced upward during the working of the machine will flow into one of the pockets d², and as the pocket is connected with the bottom of the passage-way by the pipe f the quicksilver will flow back into the passage-way near the bottom thereof.

The inner shell C' is formed on its outer face with what I term a "series" of short shelves or ledges h, which are arranged spirally to nearly the upper edge of said shell. These shelves or ledges extend within the pathway b² and serve as obstructions to check the material moving upward too freely within the pathway b², thus thoroughly subjecting the same to the action of quicksilver. Said shelves or ledges f also serve to break up or

crush any large particles or pieces of ore which may be forced into the passage-way b^2 by the worm-hub B' .

In operation the material to be worked is placed within the hopper B^3 and is gradually forced downward during the rotary motion of the same and shell C between the cone-shaped hub B' and the conical wall C' of the shell into the pathway b^2 by means of the worm-threads a' . As the feed of the material into the hopper continues the material is forced upward within the pathway b^2 until expelled over the rim a of the amalgamating-pan. During the upward travel of the material through the pathway b^2 the precious metal amalgamates with the quicksilver within the pan B and, being heavier than the base material, will sink downward and remain within the pan. The quicksilver which may be splashed or forced upward by the rotation of the inner shell is caught in one of the pockets d^2 and, as before stated, is returned within the pan by means of the pipes f . After a given quantity of material has been worked or treated the inner shell is raised clear of the amalgamating-pan and the amalgam removed from within the same and treated in the usual manner to extract the precious metal therefrom. It will be understood that sufficient water is introduced within the hopper with the material to properly wash the same.

That portion which I have termed a "drive-hopper," which is in effect a hollow cone-shaped pulley, is important in that all added drive pulleys or drums are dispensed with and the power is transmitted directly to the hopper, which, owing to its conical form, permits the changing of the speed of the shell.

Having thus described my invention, what I claim as new, and desire to secure protection in by Letters Patent, is—

1. In an amalgamator, the combination with the stationary amalgam-pan, of the central cone-shaped worm-threaded hub upwardly projecting therefrom, the rotatable shell fitted within said pan so as to form an annular passage-way which holds an amalgamating-bath, an inclined central wall in said shell which fits over the cone-shaped hub of the

pan, a drive-hopper attached to the central 50 wall of the shell, and a central supporting-shaft connected to the wall of the hopper.

2. In an amalgamator, the combination with the stationary dish-shaped amalgam-pan, of the central cone-shaped worm-threaded hub 55 upwardly projecting therefrom, a series of pockets formed in the said pan near its upper edge, a pipe connection between said pockets and the bottom of the pan, a rotatable shell provided with an inclined central wall fitted 60 within the amalgam-pan so as to leave an annular passage-way between the shell and pan and the inclined wall and cone-shaped hub, a series of shelves or ledges projecting from the outer wall of the shell, a drive-hopper at- 65 tached to the inclined inner wall of the shell, and a central supporting-shaft connected to the hopper.

3. In an amalgamator, the combination with the stationary amalgam-pan, of a series of 70 pockets formed therein near its upper edge, a pipe connection between said pockets and the bottom of the pan, a rotatable inner shell fitted within the said pan so as to form an annular passage-way which holds an amalgam- 75 mating-bath, a series of shelves or ledges projecting from the outer wall of the shell, a feed-supply for the material, and of devices for forcing the material into and through the bath contained in the annular passage-way. 80

4. In an ore-treating apparatus, the combination with a pan, of a rotatable shell therein and a cone-shaped drive-pulley having a hollow center constituting a hopper for the pan. 85

5. The combination with an amalgamating- 85 pan having inclined walls and a series of independent pockets formed in the walls pipes without the pan leading downward from the pockets into the pan, and a rotatable shell in the pan, substantially as described. 90

In testimony whereof I affix my signature, in presence of two witnesses, this 13th day of August, 1897.

ERNEST J. VERRUE.
